UNITED STATES PATENT OFFICE.

JOHN R. LONG, OF AKRON, OHIO, ASSIGNOR, BY MESNE ASSIGNMENTS, TO WILLIAM A. BYRIDER, OF AKRON, OHIO.

BENCH-VISE.

1,113,664.

Specification of Letters Patent.

Patented Oct. 13, 1914.

Application filed February 10, 1913, Serial No. 747,214. Renewed May 28, 1914. Serial No. 842,812.

To all whom it may concern:

Be it known that I, JOHN R. LONG, a citizen of the United States, residing at Akron, in the county of Summit, and State of Ohio, have invented certain new and useful Improvements in Bench-Vises, of which the following is a specification.

This invention has reference to improvements in bench vises, and the invention consists in the construction and combination of parts substantially as shown and described and particularly pointed out in the claims.

In the accompanying drawings, Figure 1 is a side elevation of one form of my new and original construction of vise, and Fig. 2 is a longitudinal sectional elevation thereof. Fig. 3 is a bottom view of said form of vise, and Fig. 4 is a cross section corresponding in the main to line 5—5, Fig. 1. Fig. 5 is a side elevation of a slightly modified construction of vise partially shown in Fig. 4.

The entire structure as thus shown is made of drop forged steel and comprises the two jaw members *c* and *d* respectively, the guide bar *b* and the keeper or yoke *k*.

The member *c* is the base member proper in both forms and in Figs. 1 and 2 is shown as having a flat circular seat support on a fixed base *b'* and rotatably secured thereon by screw *s*. The construction of the said base member also is original in this, that it is substantially elbow-shaped or right angled between its jaw and bottom portions and has a central bore axially at the base of the jaw portion adapted to receive the internally threaded tubular shank or stem 3 of the bar *b*. The tightening screw 4 enters the stem 3 of the said tubular shank and bears against the part *c* when it is tightened by means of the handle *h* therein. The said screw has a collar 5 and the part *c* has an overhanging lug having in its under face a concave slot with an outer lip 6 which confines said collar and thereby the said screw and also provides a bearing therefor. The said screw must be engaged in said slot first and then the bar *b* and its stem 3 are inserted and connected with the said screw. This being done the collar 5 is necessarily confined in the said slot and cannot escape.

The adaptation of the jaws to the work is by sliding jaw *d* bodily on said bar *b* and the keeper *k* serves as the medium for confining said jaw and holding it in working position

as it is moved here or there by hand. Thus, in case the vise is to be tightened on an object, the jaw *d* will be followed by hand and thus effect the primary gripping of the object between the jaws. Then by turning screw 4 by means of handle *h* the gripping and locking of the parts is made effective. A very short movement of the bar *b* usually is sufficient for this purpose, and an equally short reverse movement of the screw will loosen and release the object in the vise because, as shown, both the jaw *d* and yoke *k* are usually locked together on the said bar by the screw 7 and must move together, necessarily, when the jaws are opened in this way. This manner of working is common, especially for doing standard work of a given size or kind and which avoids repositioning of the jaw every time the vise is opened. Otherwise the screw 7 may be loosened and the yoke and jaw *d* be separately movable.

Incident to the foregoing I employ a dog 8 which is pivoted in its angle at 9 in the base *c* at its outer end between two right angled projections 10 thereon and having its heel in friction engagement with the circular hub of the said base *b'*. A screw 12 through the outer portion of said dog engages the bottom and end of bar *b* and forms a rest therefor, and a pin 13 through the said projections 10 limits the rearward movement of bar *b*. It follows that when a back pressure is exerted in clamping the jaws together it will manifest itself downward upon the outer end of bar *b* upon screw 13 and the dog 8 will lock on the hub of base *b'* accordingly and prevent rotation of the vise. But when the jaws are loose the vise is free to be turned on its base. Respecting the said parts *b* and *d*, it is to be observed, also, that both have flat straight meeting edges, and that the jaw *d* has side ears 11 at its front and bottom lapping upon the sides of body *b* and serving to guide it thereon. Otherwise the yoke or keeper *k* serves as the confining as well as the actual locking member for said jaw. It will also be observed that the opposite or outer edges of the said parts *b* and *d* are at opposite inclinations to the straight meeting inner edges, and the degree of inclination is considerably greater in the edge of the said jaw than in the edge in the said bar, and yoke *k* being constructed to fit snugly upon both edges at the same time its

95

105

110

full depth it follows that said yoke must itself sustain an inclined position as to the axis of bar *b* in order to engage both said inclined edges its full depth from front to rear. The inclination of the said yoke therefore is greater at its top over the jaw *j* than at its bottom over bar *b*, and is such as to make a complete binder of said yoke about said parts when it is moved up to holding position. The said parts *b* and *d* may therefore be considered as having practically a wedge shape but the taper of one part runs toward the swell of the other, and the keeper *k* is adapted to come into locking position thereon in whatever position the jaw *d* may be placed as between the extremes of its adjustments on the bar *b*.

The base or fixed member *c'* in Fig. 5 has a straight bottom 16 with side lugs or ears 20 17 adapted to be secured directly to a work bench or the like. The base *b'* has lugs 17 like part *c'* and may be fixed in any suitable position for use. This provides a guide and slide for the bar *b* at its rear end while its 25 front end is extended through the bore of the base member *c* and slideable therein within limits. Both the upper and outer edge of the jaw member *d* and the bottom edge of the bar *b* are rounded or segmental in 30 cross section.

Jaw *d* and yoke *K* are preferably connected by a spring either a coiled spring 14 as in Fig. 1, or a bow spring 15 as in Fig. 5, whereby when the yoke *K* is pushed back by 35 hand-engagement with screw handle 7 the jaw *d* is made to follow. The top edge 18 of the tapering extension or base of jaw *c* is preferably parallel with the inclined bottom edge of bar *b* so that the yoke *K* must 40 in any event be limited in its separable movement from bar *b*.

What I claim is:

1. In vises, a base member constructed to be fixed upon a suitable support and having 45 a jaw, a bar having a body inclined from its rear toward its front end on its under edge and having means to provide a limited adjustment thereof lengthwise on said member, a secondary jaw having a shank inclined 50 reversely to said bar on its upper edge and a yoke slidably mounted over said bar and said secondary member and flaring to conform to said member and said bar respectively.
55. 2. A vise having an elbow-shaped jaw member with a bore through the angle thereof, a bar having a tapered body pro-

vided with a threaded stem projecting into said bore and a screw engaging said stem and adapted to adjust said bar longitudinally, in combination with adjustable means supporting the outer end of said bar and a movable jaw and yoke slidably mounted on said bar.

3. In vises, a bottom jaw member and a 65 base therefor, a tapered bar slidably mounted on said member and means to adjust the said bar longitudinally, in combination with a movable jaw having a tapered shank and a yoke to operatively confine the same, a 70 pivoted dog at the rear of said bottom jaw member and means adapted to cause said dog to lock on said base when pressure comes on said bar.

4. A vise as described having two jaw 75 members and a combined supporting and locking bar mounted on one of said members and having the other member slideable thereon and a slideable yoke about said bar and the said jaw member mounted thereon.

5. A vise comprising a base member having a fixed jaw, a bar tapered in the direction of said fixed jaw and adjustably supported on said base member, a secondary jaw slideable on said bar, and a flaring yoke 85 about said secondary member and said bar adapted to hold the said parts in working relations.

6. In vises, a base jaw member constructed to be fixed to a suitable bottom support, a 90 tapered bar adapted to slide within limits on said base member and a secondary jaw having a tapered shank and seated on said bar, said bar and said secondary jaw having their tapers running in opposite directions, and a yoke about said parts flared to 95 conform to said tapers.

7. In vises, a pair of jaw members and a bar and a yoke operatively connected therewith, the lower of said jaw members having a bore through the base of the jaw thereon and provided with a transverse slot at the outer portion of said bore and a confining lip next in front of said slot and a screw through said bore engaging in said bar and 105 having a collar confined in said slot by said lip.

In testimony whereof I affix my signature in presence of two witnesses.

JOHN R. LONG.
